UNITED STATES PATENT OFFICE.

JOSEPH MCKAY, OF TROY, NEW YORK, ASSIGNOR TO HALL, HARTWELL & COMPANY, OF TROY, NEW YORK, A FIRM COMPOSED OF WILLIAM L. HALL, JOSEPH MCKAY, JOHN P. SCHAD, AND BURTON K. WOODWARD.

FOLD-COLLAR.

1,101,753.

Specification of Letters Patent. Patented June 30, 1914.

Original application filed April 9, 1910, Serial No. 554,320. Divided and this application filed October 26, 1912. Serial No. 727,933.

To all whom it may concern:

Be it known that I, JOSEPH MCKAY, a citizen of the United States, residing at Troy, county of Rensselaer, and State of New York, have invented certain new and useful Improvements in Fold-Collars, of which the following is a specification.

The invention relates to such improvements and consists of the novel construction and combination of parts hereinafter described and subsequently claimed.

Reference may be had to the accompanying drawings, and the reference characters marked thereon, which form a part of this specification. Similar characters refer to similar parts in the several figures therein.

In the use of the prevailing styles of fold-collars, it is customary to wear a scarf or tie which passes around the neck of the wearer between the band and the folded-over top of the collar. By the usual manner of manufacture, fold-collars are produced characterized by irregularity and variation in the width of space between the band and folded-over top opposite the lower edge of the band along the back and sides of the collar, leaving at certain points more space than is necessary for the tie, while at other points said space is so narrow and restricted as to impede the free sliding movement of the tie in knotting the same.

This application is a division of an application filed by me April 9, 1910, Ser. No. 554,320, for the manufacture of fold collars for which Letters Patent were issued November 26, 1912, No. 1,045,724.

The principal object of the present invention is to insure the provision in a fold collar of a tie-space of substantially uniform width extending around the back and sides of the collar between the band and top thereof from a point near one end of the collar to a point near its other end. I have ascertained that this object can be accomplished by cutting in the manner hereinafter described, the edges of the top and band which are secured together in completing the collar.

Other objects will appear in connection with the following description.

Figure 1 of the drawings is a plan view of the top and band of a fold-collar having their juxtaposed edges cut on like lines and adapted to be secured together to form a

fold-collar embodying my invention. Fig. 2 is a bottom plan view of a fold-collar embodying my invention.

In the manufacture of fold-collars, the connected edges of the top and band are cut along lines more or less curved in whole or in part, so that when the top is folded over and the collar bent to circular form, the top and band diverge downwardly at a greater or less angle, which angle varies in different parts of the same collar as made by methods heretofore employed. Such divergence provides the space between the band and top which receives the necktie. As heretofore practised, it has been customary to lay out the patterns for the longer sizes by projecting to the proper distance apart, the halves of a pattern for a shorter size, and then filling in the gap along lines approximately straight or varying materially from the lines of curvature immediately adjacent to the filled-in portion. The connected edges of the top and band of collars cut from such patterns would thus present a more or less irregular line, beginning at a point near one end of the collar and ending at a point near the other end thereof. It has also been customary to cut the edge of the top which is connected with the band along different lines from the edge of the band which is connected therewith, in order to secure greater

"spring" in the collar, that is, a greater angle of divergence between the top and the band. Collars made by such methods are found to vary materially in the width of the tie-space in the different sizes of collars, while in the individual collar, the tie-space is found to vary in width at different points along the back and side portions of the collars. I have ascertained that these objectionable features can be overcome, by cutting upon like lines, preferably arcs of the same radius, from a point near one end of the collar to a point near the other end thereof the edges of the top and band which are connected together in completing the collar.

Referring to the drawings wherein the invention is shown in preferred form, 1 is the top and 2 the band, each of which may be made of the usual number of plies of fabric. The juxtaposed edges of the band and top, as shown in Fig. 1, are secured together by known methods in the manufacture of the

collars. I have shown these juxtaposed edges of the top and band cut respectively upon arcs, 3 and 4, of the same radius from a point near one end to a point near the other end of each. By varying the radius of these like arcs, any desired degree of divergence can be secured between the top and band in the completed collar; and in employing the invention in the manufacture of collars of different heights and lengths, I preferably cut such edge-portions of the tops and bands for collars of different heights upon arcs, the radii of which vary in accordance with the heights of the collars, while for different lengths of collars of the same height, I employ longer or shorter arcs of the same radius.

In the finished collar folded and bent to circular form, it will be found that the top and band diverge at a substantially uniform angle, providing a tie-space of substantially uniform width throughout the extent of the arcs, 3 and 4. For the purpose of facilitating the adjustment of the scarf or necktie, it is necessary to provide ample width of space between the band and the top only at the back and side portions of the collar; as at the front of the collar, the ends of the collar-top are unrestricted by the curvature of the collar and freely yield to the manipulation of the tie. For sightliness, it is desirable in many styles of fold collars to have the ends of the collar-top sit in as closely to the band as the tie will permit. To secure this effect, I preferably cut the end-portions of the tops and the corresponding portions of the bands which are to be attached thereto, along lines differing from the arcs, 3 and 4, and prefer-

ably reversely curved relatively to said arcs, as shown at 5 on the top and 6 on the band, whereby the angle of divergence between the band and top is greatly reduced, or practically eliminated, at the front of the collar, whereat reduction in width of tie-space does not materially restrict the sliding movement of the scarf or tie. The collar will thus have a close fitting front effect, as shown at 7 in Fig. 2, while provided with a tie-space of substantially uniform and ample width at the back and sides of the collar.

What I claim as new and desire to secure by Letters Patent is—

1. A fold-collar having a top and a band of separate pieces, the connected edge-portions thereof formed on like uniformly curved lines from a point near one end of the collar to a point near the other end thereof. 55

2. A fold-collar having a top and a band of separate pieces, the connected edge-portions thereof both formed on arcs of the same radius from a point near one end of the collar to a point near the other end thereof. 60

3. A fold-collar having a top and a band of separate pieces, the connected edge-portions thereof formed on like lines, the intermediate portions of each being an arc and the end-portions being reversely curved with relation to said arc. 65

In testimony whereof, I have hereunto set my hand this 25th day of October, 1912.

JOSEPH MCKAY.
